SHEET PILER

Julius E. Graf, Avalon, and William A. Marshall,
Sharon, Pa., assignors to American Sheet and
Tin Plate Company, a corporation of New Jersey

Application June 25, 1932, Serial No. 619,324

12 Claims. (Cl. 271—88)

This invention relates to sheet pilers and particularly to those having a support which receives the sheets and descends as the pile increases. These have not been generally satisfactory when handling metal sheets because the increment of weight of the adding load results in a very irregular descent, one of the objects of the present invention being to improve the operation of such pilers in this respect. Another object is to pile sheets or plates so as to enable easy inspection of the top ones at all times. Other objects may be inferred from the following disclosure of one specific form of the invention, which is particularly intended for use at the delivery of a tin plate cleaning and polishing machine.

The accompanying drawings illustrate this specific form as follows:

Figure 1 is a front elevation.

Figure 2 is a cross-section from the line II—II in Figure 1.

Figure 3 is an end elevation.

Figure 4 is a detail of the braking mechanism.

Figure 5 is a side view of an inching switch controlling the mechanism shown in Figure 4.

Figure 6 is an end view of Figure 5.

Figure 7 is a wiring diagram.

Figure 8 is a vertical longitudinal cross-section of a power device for moving the piled sheets from the piler.

Figure 9 is a top plan of Figure 8 showing the various power connections, and

Figure 10 is an end elevation of Figure 8.

This piler is constructed for use with a double plate cleaning and polishing machine and comprises duplicate co-related units. Each consists of a pair of vertical channel bars 1 having their open faces mutually opposed to form a vertical guideway. Parallel horizontal shafts 2 and 3 are carried on plates 4 arranged to run vertically in these channel bars on wheels 5 fixed on the shafts. The upper shaft 2 carries horizontal arms 6 which have depending ends 7 contacting the shaft 3. These arms form the descending pile support which receives the tin plate from the delivery rolls 8 of a cleaning and polishing machine 9.

This support is controlled by cables 10 which are wound on drums 11 passing down beneath the shaft 3 and are fixed through the medium of an adjustable rod 12 to brackets 13 fixed to and near the tops of the end plates 4. The driving shaft 14 is journaled near the tops of the channels but out of the path of the rollers 5, it being possible to raise the support above this shaft

because the cables 10 will be lifting from the axis of the shaft 3. Rotation of the shaft 14 is controlled as follows.

The shaft 14 carries a gear 15 on its outer end, which is meshed with a pinion 16 fixed on a shaft 17. This shaft has a squared end, so a crank may be applied to manually raise the support, and turns a ratchet wheel 18 which drives a gear 19 through a pawl 20. This ratchet and pawl drive is arranged so that when the shaft 17 is turned in support raising direction the gear 19 will be free, and when the shaft turns in descending direction the gear 19 is driven. The gear 19 is meshed with a pinion 21 fixed on a shaft 22.

Rotation of the shaft 22 is controlled by an electromagnetic brake 23. This brake is controlled by an electromagnet 23^a and is novel in that its operating armature 24, which is normally urged by a spring 24^a to apply pressure to the band 24^b, carries an arm 25 which strikes a lever 26 the moment the brake is released by energization of the magnet. The illustrated braking mechanism is purely diagrammatical and may be substituted by the conventional commercial product. The lever 26 is really a switch and carries a contact 27 which rises from a contact 28. These contacts 27 and 28 are connected in series with the solenoid of the brake so that as soon as the brake is released its circuit will be broken and it will immediately reapply braking force to the shaft 22. The lever 26 and the two contacts are carried on a bracket 29 which may be raised and lowered by a screw 30. This last enables some adjustment of the brake releasing period. This brake construction is provided to prevent release of the shaft 22 except for a very short period or periods.

The above brake construction is important because it prevents the free drop of the load through any great distance. Therefore, when the support is heavily loaded it will be impossible for it to drop a distance sufficient to produce a velocity factor where kinetic energy results which the brake 23 cannot control. On the other hand, when the support is but lightly loaded the drop is still free and permits proper descent. Of course, it may be necessary to energize the brake 23 several times when the support is only lightly loaded to produce the same result which one energizing may produce when it is heavily loaded. Energizing as here used is intended to mean a single impulse to the solenoid of the electromagnet which, as stated, is very shortly or practically immediately broken by separation of the

contacts 27 and 28. It is believed that this method of controlling the descent of a loading piler by means of a series of very short unit distance drops or jerks is new, that is, the control 5 of the velocities of the descending load to factors preventing excessive energy.

The channels 1 support horizontal bars 31 which may adjustably carry side and front guides 32 and 33 and a catcher 34 which may be swung 10 down to receive the sheets being delivered from the cleaning machine when the load on the support is being removed. This catcher is a pair of Y-shaped arms mounted on a shaft 35 whose rotation is controlled by a small hand 15 catch 36. It is to be noted that the front guide 33 depends directly from the catcher 34 so that when the latter is swung horizontally the guide will be swung out of the way and permit removal of the piled sheets.

20 One of the side plates 32 of each unit carries an inching switch 37 constructed to close the circuit to the solenoid of the electromagnet 23 each time the sheet pile rises. Preferably, this switch consists of a swinging non-magnetic 25 bracket 38 which carries a solenoid 39 and a mercury switch 40. This mercury switch is the one controlling the electromagnet. The solenoid 39 is arranged to create a flux path through pole pieces 41 whose faces oppose the sheet pile. When 30 this pile is below these pole pieces their flux path is open and the bracket 38 swings so that the mercury switch 40 is open. As the pile increases in height the density of the flux path also increases until it reaches a point where the 35 bracket 38 is swung towards the sheet pile and the mercury switch 40 is closed. This energizes the electromagnet of the brake 23 and the descent of the support begins. As stated, it does this in a series of short falls, preferably between 40 one-half to one inch, and its control is never lost. As soon as the sheet pile falls somewhat the flux path between the pole pieces is again broken and the bracket 38 swings to switch-opening 45 position.

45 The arms 6, which constitute the sheet pile support, are arranged so that when in their lowermost position they straddle a raised platform 42 on a buggy 43. This platform then receives the weight of the pile and the buggy 43 may be 50 rolled away from the piler. The arms of a lift-type tractor may then be run under the platform 42 and it and the pile carried to its destination. Another platform is then substituted for the one removed and the buggy 43 run back 55 into the piler. During this operation the catcher 34 is utilized to catch the tin plate which may now be removed manually and placed on the top of the new pile. Also, during this time the shaft 60 17 was manually rotated so that the arms 6 were raised to their uppermost position so that the pile could be started. These arms may, of course, be raised, while the buggy 43 is still away from the piler awaiting the arrival of the tractor, and immediately begin to receive more sheets.

65 60 The above buggy is preferably provided with a revolvable top 43a. This permits insertion of the tractor's arms beneath the platform 42 regardless of the former's direction of approach as this top may be turned when the buggy is removed from the piler.

The wiring diagram shows the electric circuit and includes a lamp 45 in series with the solenoid of the magnetic switch which serves the dual purpose of showing that the switch is operating and cutting down the voltage from that

necessary to operate the electromagnetic brake. In addition, a limit switch 44 is supplied to break the circuit to the brake, this being arranged in the path of the pile support to prevent its descent beyond the point where its load is deposited on the buggy. The switches 37 and 44 and the contacts 27 and 28 are all in series with the magnet 23 of the brake 23.

If desired, power apparatus may be provided to roll the buggy 43 away from the piler. For 10 instance, a cylinder 46 may be fixed to the piler beneath the buggy. This cylinder contains a plunger 47 fixed to a connecting rod 48 which passes through a stuffing box 49 in the front end of the cylinder. This connecting rod is mounted 15 to a carriage 50 which runs on the floor and carries a cross-head 51. This cross-head is removably fixed to the carriage by a pin 52 and has hooked ends 53. The buggy is provided with depending arms 54 which are journaled to swing 20 outwardly on shafts 55 and positioned for engagement by the hooked ends of the cross-head.

Air is supplied to both ends of the cylinder by means of a four-way valve 56 and suitable connecting pipes. The pipe connecting the valve 25 to the front end of the cylinder is provided with flow restricting valves 57 and 57a, the latter valve being arranged to exhaust directly to the atmosphere. In operation, the valve 56 is first turned to admit air to the front end of the cylinder. It is then turned to admit air to the rear end of the cylinder, and the cross-head 51 moves the buggy. Because of the air compressed in the front end of the cylinder, which must exhaust slowly through the valves 57 and 57a, rapid 30 acceleration is prevented. When the plunger 47 reaches the end of its stroke the valve 56 is again turned to admit air to the front end of the cylinder so that the plunger 47 returns to its original position, the inclined locks of the hooked 35 ends 53 forcing the rear pair of depending arms 54 outwardly and allowing them to gravitally drop inwardly for engagement. The four-way valve 56 is again turned to admit air to the rear end of the cylinder 46, and the buggy is rolled 40 entirely clear from the piler. After the buggy is relieved of the pile the cross-head 51 is removed from its carriage and replaced in a reverse position. Then by proper reverse manipulation of the valve 56 the buggy can be rolled back to its 45 pile receiving position.

Although a specific form of this piler has been shown and described in accordance with the patent statutes, it is not intended to limit the scope of the invention exactly thereto, except as defined by the following claims.

We claim:

1. A sheet piler including a descending pile support, releasable means arranged to control the descent of said support, a solenoid arranged to release said means, and contacts constructed and arranged in series with said solenoid's energizing circuit and to separate when said means is released.

2. A sheet piler including a descending pile support, releasable means arranged to control the descent of said support, a solenoid arranged to release said means, contacts constructed and arranged in series with said solenoid's energizing circuit so as to separate immediately when 70 said means is released, and switching means also in series with said solenoid's energizing circuit and arranged to close as the level of the pile on said support rises.

3. A sheet piler including oppositely facing 75

- vertical channel bars, a pile support including horizontal roller-ended shafts running in said channel bars and respectively positioned by supporting plates and having horizontal arms extending from the upper one of these shafts, drums arranged adjacent the top of said channel bars, cables wound on said drums and liftingly connected to said pile support at points beneath said upper shaft thereof, means for turning said drums in support raising direction, means for braking or allowing said drums to intermittently turn in support lowering direction, and means for causing said last named means to allow said turning movement when the pile on said support rises above a predetermined level.
4. A sheet piler including a catcher for holding sheets while the piler is being unloaded, said catcher comprising vertically swinging aligned Y-shaped arms opening toward the delivering direction of the sheets being piled, and releasable means for holding said arms in horizontal or vertical positions.
5. A sheet piler including lateral guides, an end guide and a sheet catcher, said catcher including vertically swinging aligned Y-shaped arms opening towards the delivering direction of the sheets being piled and said guide being carried by said catcher in alignment therewith.
6. A steel sheet piler including a gravity operated descending pile support, an electromagnetically operated brake arranged to control the descent of said support and a switch arranged to control said brake, said switch including means for creating a magnetic flux path at a position where the edges of sheets on said support are in the same and means for effecting its operation by an increase or decrease in the density of said flux path caused by the number of said sheets.
7. A steel sheet piler including a gravity operated descending pile support, an electromagnetically operated brake arranged to control the descent of said support and a switch arranged to control said brake, said switch including means for creating a magnetic flux path at a position where the edges of sheets on said support are in the same and means for effecting its operation by an increase or decrease in the density of said flux path caused by the number of said sheets, and said brake being associated with means for limiting its operation to a series of momentary releasals regardless of the controlling operation of said switch.
8. A steel sheet piler including a pile support, means for guiding moving sheets to said support, said support and said means being relatively movable so that the latter may guide sheets to the top of an increasing pile of the same on the former, means for effecting relative movement between said support and the first named means and a switch for controlling the second named means, said switch including means for creating a magnetic flux path at a position where the edges of sheets on said support are in the same and means for effecting its operation by an increase or decrease in the density of said flux path caused by the number of sheets in the same.
9. A sheet piler including a sheet-pile support, means for mounting said support for free descent, a brake for restraining descent of said support, said brake being releasable so that said support can descend through distances sufficient to accommodate increases in the height of a sheet-pile thereon, and means for retarding the otherwise free descent of said support through said distances.
10. A sheet piler including a sheet-pile support, means for mounting said support for free descent, a brake for restraining descent of said support, means automatically responsive to increases in the height of a sheet-pile on said support for effecting releasals of said brake so that said support can progressively descend through distances sufficient to accommodate said increases and means for retarding the otherwise free descent of said support through said distances, the third named means functioning independently of the second named means' responses to said increases.
11. A sheet piler including a sheet-pile support, means for mounting said support for free descent, a brake for restraining descent of said support, means automatically responsive only to increases in the height of a sheet-pile on said support which are equal to the thickness of a plurality of the sheets, for effecting releasals of said brake so that said support can progressively descend through distances approximately equaling said increases and means functioning independently of the second named means' responses to said increases for retarding the otherwise free descent of said support through said distances.
12. A sheet piler including a sheet-pile support, means for mounting said support for free descent, a brake for restraining descent of said support, means automatically responsive only to increases in the height of a sheet-pile on said support which are equal to the thickness of a plurality of the sheets, for effecting releasals of said brake so that said support can progressively descend through distances approximately equaling said increases and means functioning independently of the second named means' responses to said increases for effecting quickly repeated reapplications and releasals of said brake during the otherwise free descent of said support through said distances.
